[57] **CLAIM**

The ornamental design for a media converter unit for a tape cassette for data processing display system, substantially as shown and described.

DESCRIPTION

FIG. 1 is a front perspective view of a media converter unit for a tape cassette for data processing display system showing my new design;

FIG. 2 is a front elevational view thereof on an enlarged scale;

FIG. 3 is a rear elevational view thereof on an enlarged scale;

FIG. 4 is a top plan view thereof on an enlarged scale;

FIG. 5 is a left side elevational view thereof on an enlarged scale; and

FIG. 6 is a right side elevational view thereof on an enlarged scale.
